AGGREGATE DISCHARGE SPOUT FOR DUMP TRUCKS

Harold J. Rosener, New Ulm, Minn.

Application August 24, 1953, Serial No. 375,993

6 Claims. (Cl. 298—7)

This invention relates to a gravel discharge spout 15 adapted for easy attachment to the rear of a conventional dump truck.

It has long been a problem to maintain a smooth continuous surface between hard surface highways and the shoulder strips running along the sides thereof. Drainage water washes away the soft shoulder portion adjacent the edge of the hard surface and produces a rut which is dangerous to vehicles running off of the paved surface. It is difficult to maintain a smooth continuous shoulder surface adjacent the paved strip and to keep this rut filled with suitable aggregate material.

It is an object of this invention to provide an attachment for conventional dump trucks specifically for the purpose of filling such ruts in the road shoulders adjacent the edge surface of the highway strip.

It is another object to provide an easily attached discharge spout adapted to receive and guide a steady stream of aggregate filler material down onto the road surface adjacent the highway strip thereof and to controllably vary the elevation of the top surface of the filler aggregate relative to the adjacent marginal edge portion of the hard surface highway strip to ultimately permit a smooth and substantially continuous surface to be obtained between the shoulder and said hard surface pavement.

More specifically, it is an object to provide a pivotally mounted, easily retractible and easily detachable discharge spout of the class described for discharging a controllable stream of filler aggregate for maintaining the shoulder strips of adjacent hard surface roadways.

It is still another object to provide a novel and highly efficient mounting for a discharge spout of the class described.

These and other objects and advantages of my invention will more fully appear from the following description made in connection with the accompanying drawings wherein like reference characters refer to the same or similar parts throughout the several views, and in which:

Fig. 1 is a longitudinal sectional view partially in side elevation showing my discharge spout in attached position on the rear of a conventional dump truck;

Fig. 2 is a top plan view thereof showing the beveled guiding partitions in the rear of the dump body of the truck with said dump body tilted into dumping position;

Fig. 3 is a rear end view of my discharge spout attached to the dump body of a truck;

Fig. 4 is a horizontal sectional view through the tail gate of the truck dump body showing the mounting brackets for my discharge spout; and

Fig. 5 is a perspective view of the discharge spout per se.

A conventional dump truck body 7 is illustrated in the accompanying drawings and has a tail gate 8 with a center discharge opening formed therein. A pair of beveled partitions 9 are fixed across the rear corners of the dump body 7 to guide the aggregate into the opening 8a in the tail gate 8.

A pair of upstanding side panels 10 are securely fixed in rearwardly extending relation to the tail gate 8 adjacent

2

the sides of discharge opening 8a, as best shown in Figs. 1 and 4, and a material guiding apron 11 is fixed to the tail gate 8 along the lower edge of said opening 8a and traverses the distance between the two side panels 10.

5 A plurality of rod receiving notches 10a are formed in the upper edge portions of said panels 10 and transversely corresponding notches of said panels form a pair of cradles in which a chute mounting rod, to be hereinafter described, is pivotally received. An anchoring aperture is provided through an intermediate portion of each of the side panels 10 and said cradle forming notches 10a of each of said panels are arranged along the arcuate circumference of a circle with said anchoring aperture taken as a center for purposes that will hereinafter be set forth.

A discharge spout having a cylindrical portion 12 is provided and has a curved elbow portion 12a at the lower end thereof to form a generally circular discharge mouth lying in a substantially horizontally disposed plane. A receiving and guiding hopper 13 is formed at the upper end of the discharge conduit 12 and the forward end of said hopper 13 has a generally rectangular shaped box 13a which surrounds the discharge mouth opening 8a and is of a size to receive the mounting panels 10 and apron 11 therewithin. The box portion 13a has a pair of upstanding side panels which overlap the upstanding panels 10, as best shown in Figs. 1, 2 and 3, and are disposed in slightly spaced relation outwardly therefrom. A straight bottom panel or plate 13b extends rearwardly from the upper end of cylindrical spout portion 12 to the rear ends of the panels 13 and underlies the apron 11, as best shown in Fig. 1.

The hopper 13 is pivotally anchored to the tail gate 8 on the trunnion forming mounting rod 14 which extends between the side panels of box 13a, as best shown in Figs. 1, 2 and 5. Said trunnion rod 14 is selectively received in a pair of transversely opposed cradle notches 10a. The weight of the rearwardly extending hopper 13 and cylindrical spout portion 12 maintains the forward edge of the underlying hopper plate 13b in abutting relation with the lower portion of the tail gate 8 when the dump body is in normal lowered position but the pivotal mounting of said hopper 13 on the mounting panels 10 permits the same to swing upwardly when the lower end thereof is in ground supported discharge position with dump body in dumping position as best shown in Fig. 1. Suitable means for positively anchoring the trunnion rod 14 in the selected pair of cradles are provided, such as the pair of anchoring hooks 15, each having a laterally outwardly extending attachment pin 15a adapted to be mounted through the anchoring aperture through the intermediate portion of each of the upstanding mounting panels 10, as best shown in Figs. 1 and 4. Obviously, the distance from attachment pin 15a to the closed end of hook 15 is always the same, therefore requiring that the distance from said aperture to the trunnion rod 14 always be the same. Therefore, by positioning said notches 10a along a circular arc described with said anchoring aperture as a center, permits said trunnion rod to be maintained at the same distance from the anchoring aperture regardless of the selected trunnion cradles in which the rod 14 is mounted. Suitable means are, of course, provided for securing the pin 15a of each hook 15 to said side panel, such as a threaded nut 15b, best shown in Figs. 1 and 4.

A pavement engaging supporting wheel 16 supports the lower mouth portion in predetermined relation to the pavement surface and is mounted adjacent the lower discharge mouth of elbow 12a, as shown in the drawing. 70 The wheel 16 is connected to a vertically adjustable mounting bracket 17 which is adjustably mounted on an upstanding mounting arm 18 fixed to the lower dis-

charge mouth portion of elbow 12a. In the form shown, a reinforcing band 12b surrounds said mouth portion, and arm 18 is fixed thereto. When not in use, the discharge spout may be swung upwardly on its trunnion rod 14 into the dotted position shown in Fig. 1 and is securely held in upstanding inoperative position by hooks 19 pivotally mounted on the upper portion of the tail gate 8 and interfitting with a pair of laterally outstanding pins 20 fixed to the upper rear portion of the hopper box side panels 13a, as best shown in Figs. 1 and 5. When the spout is disposed in upstanding position, the discharge opening in the tail gate is, of course, closed in any suitable manner, such as by a removable closure panel (not shown).

In operation, the gravel or other filler aggregate is initially loaded into the dump body 7 of the truck while the same is in horizontal load-carrying position with the spout 12 extending substantially horizontally rearwardly from the tail gate 8 thereof. When the load is to be discharged through opening 8a and spout 12, the dump body 7 is raised into the tilted position shown in Figs. 1 and 2 positioning the discharge mouth at the lower end of elbow 12a in substantially horizontal position and engaging the supporting wheel 16 with the marginal edge portion of the pavement, as best shown in Figs. 2 and 3, to positively support the discharge mouth of the spout 12 in the desired position relative to the level of the pavement. Obviously, the level of the gravel deposited onto the shoulder along the edge of the pavement will be the same as the elevation of the discharge mouth of elbow 12a and, as shown in Figs. 1 and 3, this level will be set slightly higher than the surface of the pavement so that when the aggregate has been compacted, a smooth continuous surface will be provided between the shoulder and the pavement. It should be pointed out that the spout 12 is free to swing upwardly relative to the dump body 7 in the event that the supporting wheel 16 strikes a raised portion of the pavement. However, the weight of the rearwardly extending hopper and spout maintains the wheel in pavement engaging position and the overlapped relation between apron 11 and bottom plate 13b permits swinging of the hopper 13 and its trunnion rod 14 in its cradle notches 10a without spilling the aggregate when the wheel 16 passes over irregularities in the pavement surface. The provision to permit free upward swinging movement of the spout, if necessary, prevents damage not only to the spout itself but also to the dump body of the truck. The angle at which the straight spout portion 12 is disposed relative to the truck body can be controllably adjusted by shifting the trunnion rod 14 forwardly or rearwardly in the cradle notch 10a so that the dumping angle of the truck body can be varied while maintaining the discharge mouth of the elbow 12a in a substantially horizontal plane.

It will, of course, be understood that various changes 55 may be made in the form, details, arrangement and proportions of the parts without departing from the scope of this invention which, generally stated, consists in the matter shown and described herein and set forth in the appended claims.

What I claim is:

1. A filler aggregate discharge spout constructed for attachment to the rear of a dump truck body comprising a pair of upstanding mounting panels adapted to be fixed in transversely spaced-apart relation to the tail gate of a dump truck body adjacent the side portions of a discharge opening formed therein, said panels having a plurality of spaced recessed notches formed in the upper edges thereof to provide a plurality of respectively opposed pairs of trunnion receiving cradle elements, a spout hopper having trunnion means fixed to the upper portion

thereof to be received in selected cradle elements, abutment means formed at the lower forward edge portion of said hopper for abutting engagement with the lower portion of a truck body below the discharge opening in the tail gate thereof, means for positively anchoring said trunnions in said cradles but permitting upward swinging movement of said hopper relative to said mounting panels and said truck body when in assembled operative position, and a rearwardly extending spout portion connected in fixed relation to said hopper having a discharge mouth lying in a substantially horizontal plane when in operative position, the shifting of said trunnion means from one pair of notches to another permitting adjustment of the angular relation between said spout mouth and the dump body.

2. The structure set forth in claim 1, and means for engaging the pavement surface fixed in laterally spaced relation to the discharge mouth of said spout for positively supporting the same relative to the ground surface.

3. The structure set forth in claim 2, and said pavement engaging means consisting in a vertically adjustable supporting wheel.

4. The structure set forth in claim 1, and hook means removably mounted in said mounting panels and positively engaging said trunnion anchoring means to facilitate easy adjustability thereof for positively holding the same in the desired position.

5. The structure set forth in claim 1, and releasable means for positively locking said spout in upwardly swung retracted inoperative position when not in use.

6. A filler aggregate discharge spout constructed for attachment to the rear of a dump truck body, said spout comprising a pair of upstanding mounting panels adapted to be fixed in transversely spaced-apart relation to the tailgate of a dump truck body adjacent to the side portions of a discharge opening formed therein, said panels having a plurality of spaced, recessed notches formed in the upper edges thereof to provide a plurality of respectively opposed pairs of trunnion-receiving cradle elements, a spout hopper having a trunnion-forming rod fixed to the upper portion thereof and extending transversely thereof to be received in selected cradle elements, abutment means formed at the lower forward edge portion of said hopper for abutting engagement with the lower portion of a truck body below the discharge opening in the tailgate thereof, said trunnion-forming rod and said abutment means cooperating to support said spout hopper and to maintain the same in a predetermined angular relation with respect to the truck body and said trunnion rod being shiftable to different cradle elements to maintain a predetermined angular relation of said spout hopper with respect to the pavement in various inclined positions of the truck body, said mounting panels extending inwardly of said cradle elements, and a rearwardly extending spout for positively anchoring said trunnion rods in said cradles and permitting upward swinging movement of said hopper about said trunnion rods when the same is carried by said cradle elements, and a rearwardly extending spout portion connected in fixed relation to said hopper having a discharge mouth lying in a substantially horizontal plane when in operative position, whereby said hopper and spout portion thereof may be swung upwardly into inoperative position.
